Specification for Design.

Patented July 8, 1919.

Application filed April 30, 1919. Serial No. 293,849. Term of patent 3½ years.

To all whom it may concern:

Be it known that I, LEON F. ORCUTT, a citizen of the United States, residing at New York, in the county of New York and State of New York, have invented a new, original, and ornamental Design for Printed Silk, of which the following is a specification, reference being had therein to the accompanying drawings.

The figure is a plan view of a piece of printed silk showing my new design.

I claim:

The ornamental design for printed silk, as shown.

In testimony whereof I hereunto affix my signature.

LEON F. ORCUTT.
